UNITED STATES PATENT OFFICE.

PETER SCHERMAN, OF FORT ATKINSON, WISCONSIN.

FURNACE-GRAVE.

1,303,119.

Specification of Letters Patent.

Patented May 6, 1919.

Application filed December 17, 1915. Serial No. 67,375.

To all whom it may concern:

Be it known that I, PETER SCHERMAN, a citizen of the United States, residing at Fort Atkinson, county of Jefferson, and State of Wisconsin, have invented new and useful Improvements in Furnace-Grates, of which the following is a specification.

My invention relates to improvements in furnace grates for stationary and locomotive 10 boilers and heaters.

The object of my invention is to provide means for forcibly delivering air or steam against the under surface of the grate and between the grate bars for the triple purpose 15 of cooling the bars, facilitating combustion, and driving the flames and products of combustion in a direction to secure maximum heating efficiency.

In the drawings—

20 Figure 1 is a fragmentary plan view of a furnace or fuel grate embodying my invention.

Fig. 2 is a sectional view of the same, drawn on line $x-x$ of Fig. 1.

25 Fig. 3 is a sectional view, drawn on line $y-y$ of Fig. 2.

Fig. 4 is a fragmentary plan view showing a modified form of end plate.

30 Fig. 5 is a vertical sectional view, drawn to a plane cutting the valve slide and air ports.

Fig. 6 is a transverse sectional view, drawn to a vertical plane cutting one of the air ports.

35 Fig. 7 is a detail view of one of the valve slides.

Like parts are identified by the same reference characters throughout the several views.

40 The grate proper illustrated in the drawings may be of ordinary construction, the frame having end plates A and oscillatory grate bars B, the latter being journaled in the side bars C of the frame and also in center frame bars D, where the furnace is so large as to require intermediate supports.

45 The grate bars B are provided with downwardly projecting arms B' which are connected with shaking bars B'', the latter being 50 loosely connected with a shaking lever b located at the front of the furnace. These parts being of ordinary construction require no further description.

In my improved construction, however, a 55 pipe E extends along the under side of the plate A and is provided with a series of up-

wardly projecting branch pipes E', which extend through apertures in the plates A and are adapted to deliver jets of air or steam upwardly through the plates in the direction 60 of the arch. The air or steam is supplied to the pipe E from the exterior through a main supply pipe F.

An extension F' of the pipe F projects rearwardly underneath the central portion 65 of the grate. In the construction shown, the axis of this extension F' is below the space between the frame bars D, D. This extension or branch pipe F' is provided with a series of apertures f through which jets of 70 air or steam may escape in an upward direction between the bars D, D.

The extension F' is also provided with lateral branches G and these branches also have jet openings g at intervals. The branches 75 are located with their axes directly below the spaces between the bars of oscillatory grate bars B, so that the jets of air or steam escaping through the openings g will pass upwardly between the grate bars B and be 80 delivered directly into the fuel.

I attach considerable importance to the arrangement of the pipes and jet apertures with reference to the various elements of the grate. The jets delivered from pipe E 85 through the ducts E' cool the plate A, protect the arch and drive the fire under the boiler. The jets from the rearwardly extending pipe F' divides the fire so that it will not strike directly on the middle of the boiler. 90 The jets deflect the flames toward the respective sides of the boiler, thereby distributing the heat more uniformly over the heat absorbing surfaces. The branch pipes G will deliver air or steam directly into the fuel and thereby greatly promote combustion. Any 95 desired number of these branch pipes may be employed.

It will of course be understood that combustion will be promoted by all the jets of air or steam, the size of the openings and the force or pressure of the air or steam being regulated to suit the requirements of the furnace. But with the described arrangement of the jets, I am able to not only 100 utilize them for the purpose of promoting combustion, but for the additional purpose of uniformly distributing the heat and to protect those stationary grate bars which would otherwise be most subject to excessive 105 temperatures from being heated to the point where deterioration will result.

Referring to Figs. 4 to 7 inclusive, it will be observed that I have provided means for covering the jet ports when it is desired to prevent ashes, cinders or small pieces of coal from lodging therein. For example, the hand plate A A, similar to the plate A, shown in Fig. 1, is provided with a channel O in which a slide bar P is mounted. This slide bar is provided with a depending arm 10 Q which extends through a slot Q' in the plate A A, whereby the bar may be manipulated from the ash pit to move it longitudinally along the channel. The bar P is provided with a series of apertures P' which 15 may be moved by means of the arm Q into and out of registry with the outlets of the branch pipes E'. The bar P is therefore adapted to serve as a slide valve, whereby the outlets of the branch pipes E' may be 20 opened or closed at pleasure. When feeding fuel into the furnace or when for any reason it is not desired to deliver air through this end plate, the slide valve may be closed, thereby preventing ashes or small particles 25 of coal or cinders from lodging in the ducts.

I claim—

1. The combination with a fuel grate provided with a stationary end plate, of a main supply pipe for air or steam, branch pipes 30 leading therefrom and provided with ducts leading through the end plate of the grate, another branch pipe leading rearwardly underneath the central portion of the grate and provided with openings through which 35 air or steam may be injected upwardly through the grate along the center line.

2. The combination with a fuel grate provided with a stationary end plate, of a main supply pipe for air or steam, branch pipes 40 leading therefrom and provided with ducts leading through the end plate of the grate, another branch pipe leading rearwardly underneath the central portion of the grate and provided with openings through which

air or steam may be injected upwardly 45 through the grate along the center line, and auxiliary branch pipes extending laterally from intermediate points in said central branch pipes and having jet apertures for delivery of air or steam upwardly through 50 the grate, substantially as described.

3. A furnace grate provided with sets of oscillatory grate bars, an apertured stationary end plate and spaced central supporting bars for the inner ends of the oscillatory 55 grate bars, in combination with a set of pipes for air or steam extending underneath the grate bars, and having apertures through which air or steam may be ejected through said end plate and between the 60 oscillatory bars and also between the central supporting bars, substantially as described.

4. A furnace grate provided with longitudinally extending bearing bars extending 65 from the fuel receiving end rearwardly, two sets of grate bars transversely arranged and supported at their inner ends upon said bearing bars, and a blast pipe located underneath said bars, and provided with apertures 70 through which air or steam may be delivered in a substantially continuous sheet through the aperture formed by said bars to divide the flames and products of combustion and force them toward the sides of the 75 combustion chamber, said blast pipe being provided with medial branches extending transversely thereto below the spaces between the grate bars, and apertured to deliver air or steam between the middle grate 80 bars and deflect the flames toward the front and rear of the combustion chamber.

In testimony whereof I affix my signature in the presence of two witnesses.

PETER SCHERMAN.
